(57) **CLAIM**

The ornamental design for kiosk having computer and peripherals, as shown and described.

DESCRIPTION

FIG. 1 is a front three-dimensional view of the invention;
FIG. 2 is a rear three-dimensional view of the invention;

FIG. 3 is a front view of the invention;

FIG. 4 is a right side view of the invention;

FIG. 5 is a rear view of the invention;

FIG. 6 is a left side view of the invention;

FIG. 7 is a top view of the invention; and,

FIG. 8 is a bottom view of the invention.
